UNITED STATES PATENT OFFICE.

JOHN A. RIEPER, OF NEW YORK, N. Y.

DESIGN FOR A BILLIARD-CUE HANDLE.

SPECIFICATION forming part of Design No. 22,974, dated December 19, 1893.

Application filed November 21, 1893. Serial No. 491,597. Term of patent 7 years.

To all whom it may concern:

Be it known that I, JOHN A. RIEPER, a citizen of the United States, residing at the city of New York, county and State of New York, 5 have invented and produced a new and original Design for a Billiard-Cue Handle, of which the following is a specification, reference being had to the accompanying drawing, which represents an elevation of a billiard-cue provided with my newly-designed handle.

The leading feature of my design consists of a billiard cue handle provided with a set of longitudinal corrugated ridges, the corrugations of one ridge breaking line with the 15 corrugations of the adjoining ridges.

The letter A represents the handle of a bil-

liard cue, provided with longitudinal ridges a, each made of undulating form. That is to say, each ridge is alternately raised and depressed, so as to be provided with a set of 20 equi-distant peaks a'. The peaks of any one ridge are placed midway between the peaks of the adjoining ridges, so that the whole presents a very rich and pleasing effect.

What I claim is—

The design for a billiard cue handle as herein shown and described.

JOHN A. RIEPER.
